UNITED STATES PATENT OFFICE.

ERNEST WEISSBRODT, OF LAUSANNE, SWITZERLAND.

WALL.

1,241,797.

Specification of Letters Patent.

Patented Oct. 2, 1917.

Application filed September 5, 1916. Serial No. 118,598.

To all whom it may concern:

Be it known that I, ERNEST WEISSBRODT, architect, a citizen of Switzerland, residing at Lausanne, Canton of Vaud, in the Confederation of Switzerland, have invented certain new and useful Improvements in Walls, of which the following is a specification.

The present invention relates to a wall and in carrying out the same I employ tiers of blocks so constructed and arranged as to provide communicating air spaces in the wall. Alternate tiers of blocks are arranged parallel to the faces of the wall so that between them a free space is provided, and the blocks in intermediate tiers are placed transversely in the wall and are provided with channels or passages so disposed as to connect the free spaces between the blocks of the alternate tiers, for the purpose of obtaining within the wall at least one air layer all the parts of which communicate with each other.

The blocks of the intermediate tiers may be provided with projections which extend into the spaces between the blocks of the alternate tiers, and these projections prevent the binding material which is placed between the different tiers from working into the channels and thus obstructing the same.

My invention is illustrated in the accompanying drawing in which—

Figure 1 is a perspective view of my improved wall, and Figs. 2 and 3 are respectively a side view and a plan view of one of the blocks of which the wall is made.

The wall as illustrated is made of two groups of tiers of blocks which are alternately superposed in a regular manner. The blocks 6 in each alternate tier are placed in two rows. All the faces of these blocks are plain, and the blocks are placed parallel to the faces of the wall; the two rows being disposed at a certain distance from one another, in order to provide an air space 6¹ between their adjacent faces. The intermediate tiers consist of rows of header blocks 5 and 7 transversely arranged with the blocks in each row placed side by side within the wall with their end faces preferably parallel to the outer faces of the blocks 6. The upper and under faces of the blocks 5 and 7 are provided with projections 3 which extend into each of the spaces 6¹ between the tiers of blocks immediately above and below the same. In the blocks 5, 7 vertical

channels or passages 4 of square or other cross-section, are provided, and extend transversely through the block so as to open into the adjacent air spaces 6¹ and thus connect the same. Within the wall, there is therefore an air space of which all parts communicate with each other. The projections 3 are of sufficient height to prevent the mortar or cement which is laid between the adjacent blocks from working into the channels 4 and thus obstructing the same, whereby the communication between the different parts of the air space is assured.

The blocks 5, 7 may further be provided with channels 2 of circular or other cross-section as is shown by the dash-dotted lines in Fig. 3.

It will be understood that I do not limit my invention to the precise construction herein shown and described, as variations may be made in the form of the blocks and in the manner of making communication between the air spaces without departing from the nature and spirit of my invention.

The blocks may be made for instance of burnt clay; of cement, of beton, of burnt earth and the like. The free spaces 6¹ and the channels connecting the same can serve for providing a circuit of cold or hot air according to the purpose to be obtained.

I claim as my invention.

1. A wall composed of tiers of blocks, the blocks in alternate tiers being placed in rows with their inner faces spaced apart, while the blocks in intermediate rows are headers which span the space between the rows of blocks in alternate tiers, and are provided with transverse passages whereby there is in the wall a plurality of air spaces each in communication with all the others.

2. A wall composed of tiers of blocks, the blocks in alternate tiers being placed in parallel rows with their inner faces spaced apart and their outer faces parallel to the surfaces of the wall, while the blocks in intermediate rows are headers which span the spaces between the rows of blocks in alternate tiers and are provided with vertical passages whereby in the wall there is a plurality of air spaces each in communication with all the others.

3. A wall composed of tiers of blocks, the blocks in alternate tiers being placed in parallel rows with their inner faces spaced apart and their outer faces lying in the surfaces of the wall while the blocks in inter-

mediate tiers are headers which span the spaces between the rows of blocks in alternate tiers, have their outer faces in the surfaces of the wall, and are provided with 5 projections extending into the spaces between the rows of blocks in alternate tiers and are also provided with vertical passages whereby in the wall there is a plurality of

air spaces each in communication with all the others.

In testimony whereof I have affixed my signature in presence of two witnesses.

ERNEST WEISSBRODT.

Witnesses:

Dr. ROD. DE WURTEMBERGER,
ELMER SCHNEIDER.
